MEANS FOR MOUNTING COPYHOLDERS ON
TYPEWRITER PLATFORMSFloyd H. Bloomstran, Jamestown, N. Y., assignor
to Art Metal Construction Company, Jame-
town, N. Y.

Application May 7, 1949, Serial No. 91,966

11 Claims. (Cl. 120—28)

1

This invention relates to improvements in brackets or supports by means of which copyholders may be mounted on typewriter platforms or similar supports.

Secretarial desks are commonly provided with platforms constituting extensions of the desks and to which typewriters or similar machines may be secured. When the typewriter is not in use, such platform with the typewriter mounted thereon may be swung or otherwise shifted into position within a pedestal of the desk. Since it is frequently desirable to use copyholders in connection with the typewriter platforms of desks of this type, difficulty has heretofore been encountered in mounting these copyholders on the platforms for the reason that the platforms are necessarily limited in their width, and furthermore, the copyholders as now commonly used are too large to be swung with the typewriter and its supporting platform into an inoperative position within the pedestal of the desk.

One of the objects of this invention is to provide a bracket by means of which a copyholder may readily be supported on a typewriter platform of a desk in such a manner that a copyholder together with a part of the bracket can be quickly and easily secured to or detached from the platform. Another object is to provide brackets of improved construction which comprises two members, one of which may be permanently secured to the platform and the other of which has the copyholder secured thereto and is releasably secured to the first bracket member. A further object of this invention is to provide brackets of strong and rigid construction which support the copyholder beyond an edge of the platform. Another object is to provide a copyholder supporting bracket with a pivotal mounting for the usual lever which is used for vertically moving a part of the copyholder. It is also an object of this invention to provide brackets of this type which can be used without interfering with the usual pedestal door of a desk.

Other objects and advantages will be apparent from the following description of one embodiment of the invention and the novel features will be particularly pointed out hereinafter in connection with the appended claims.

In the accompanying drawings:

Fig. 1 is a perspective view of a desk having a typewriter platform arranged in its operative position and having brackets embodying this invention secured thereto and supporting a copyholder.

Fig. 2 is a fragmentary elevation, partly in

2

section, approximately on the line 2—2, Fig. 1, showing in elevation the copyholder brackets supporting a copyholder, a portion of the desk platform being shown in section.

Fig. 3 is a top plan view of the brackets and a fragmentary view of the desk platform and of the copyholder.

Fig. 4 is a sectional elevation thereof, on line 4—4, Fig. 3, showing one of the brackets.

Fig. 5 is a sectional elevation thereof, on line 5—5, Fig. 3, showing the other bracket.

In Fig. 1, 9 represents a portion of a pedestal desk which is provided with a platform 8 mounted on the desk in such a manner that it can be swung into operative position as shown in Fig. 1, and into an inoperative position in which the platform together with a typewriter or other machine mounted thereon may be inserted into and housed within the pedestal of the desk. The width of these platforms is such that when a typewriter is secured thereto, there is usually not sufficient room to support a copyholder 10 on the platform. 11 represents the usual door which closes the pedestal of the desk when the platform 8 with a machine mounted thereon is housed within the pedestal.

In order to support a copyholder on the platform 8 I provide a pair of brackets 12 and 14 which are preferably made in two parts or members which are readily separable. One of these parts of each bracket is a base member 15 to which the other part or member of the bracket may be quickly attached or removed. The base members may be of any suitable construction, those shown being of Z-shaped cross section, each including a flange 16 which may be suitably secured to the platform 8 in any suitable manner, for example, by means of bolts 17 or other fastening means. Each of these base members also includes an upwardly extending flange or leg 18 terminating at its upper edge in a substantially horizontally extending flange 19 to which flange the other member of the bracket may be releasably secured in any desired manner.

The other or removable members of the brackets are preferably made of sheet metal bent or formed to include substantially flat horizontal portions 21 and 22. The portion 21 of each bracket is formed to lie face to face upon the horizontal flange 19 of the base member of the bracket. The other portion 22 of the removable member of the bracket extends beyond the outer edge of the platform 8 and the base or foot portions 23 of a copyholder may be suitably secured to the horizontal portions 22 of the re-

movable bracket members in any suitable manner, for example, by means of bolts 24 or other fastening means which extend through apertures in the foot portions of the copyholder and in the horizontal parts 22 of the brackets. Consequently, the copyholder may be more or less permanently secured to the removable parts or members of the brackets 12 and 14.

In order to firmly support the copyholder, the removable members of the brackets are reinforced to render them rigid, and for this purpose, in the particular construction illustrated, each removable member is provided between the portions 21 and 22 thereof with a reinforcing part 25, which in the construction shown is of channel or inverted U-shape. The portions 21, 22 and 25 may be formed of a single piece of sheet metal bent into the desired shape, or this part of the removable member may be made of separate pieces secured together, for example, by welding.

In some types of desks the door 11 for the desk pedestal extends at a considerable distance above the upper surface of the platform 9, and by making the reinforcing portion 25 of channel shape, this reinforcing portion serves the further purpose of receiving or straddling the upper portion of a pedestal door of this type, as shown in Figs. 4 and 5. In the particular construction shown in Fig. 1, a door is shown which does not extend materially above the upper flanges 19 of the fixed bracket members, and this door, therefore, does not extend into the reinforcing channel portions 25 of the brackets, and when used in connection with desks having doors of this type, the channels 25 may be replaced with reinforcing members of other shapes or forms. In order to prevent rattling and damage to the finish of the upper portions of the doors, the inner surfaces of the channel portions 25 are preferably lined with a suitable felt or other cushioning material 27.

In order to support the copyholder in such a manner that it is mounted rigidly on the platform 9, it is also desirable to provide a reinforcing member extending crosswise of the member or portion 25. For this purpose, the horizontal portion 21 of each of the removable parts of the brackets is provided with an upwardly extending flange 28, preferably formed integral therewith, and a truss member 30 is also provided on each bracket which straddles the reinforcing or channel member 25 thereof. This truss member is rigidly secured to the upright flange 28, for example, by welding, and the outer portion of the truss member is also rigidly secured to the horizontal supporting part 22, for example, by means of a flange 31 integral with the truss member 30, which may be welded or otherwise secured to the horizontal supporting part 22. If desired, the inner end of the truss member may also be provided with a flange or integral part 32 which may be welded or secured to the portion 21 of the removable member of the bracket.

By means of the construction described, the truss member 30 and the parts associated therewith resist flexing of the removable member of the bracket in one direction, and the reinforcing member or channel portion 25 resists flexing in a direction transversely thereof, so that a strong and rigid bracket results which can be made of relatively light gage sheet metal. Consequently, the removable bracket member does not add materially to the weight of the copyholder to which it is secured.

Any suitable or desired quickly detachable con-

nection may be provided between the two parts or members of each bracket. In the construction illustrated, this is accomplished by means of a locking bolt 35 provided at one end thereof with a web or wing 36 for turning the bolt, and at the other end thereof a locking pin 37. The bolt 35 extends loosely through a hole in the horizontal portion 21 of the removable bracket and the pin 37 is of such length as to prevent removal of the bolt through the hole in the part 21. This pin 37, when the bolt 35 is turned in one direction, cooperates with a suitable cam member, generally designated as 40, secured to the lower surface of the horizontal flange 19 of the fixed member of the bracket for pressing the portion 21 into tight engagement with the horizontal flange 19. Fastening devices of this type are well known and are, therefore, not herein described in detail. Any other suitable quickly releasable fastening device may be provided if desired.

When it is desired to connect the removable member of the bracket to the fixed member, it is merely necessary to insert the end of the bolt 35 carrying the pin 37 through an opening in the flange 19 into position to engage the cam member 40. By turning the bolt 35 by means of its handle portion 36 through slightly less than half a revolution, the pin 37 will engage the cam faces to draw the bolt 35 downwardly and thus press the part 21 into engagement with the flange 19. Similarly somewhat less than a half turn in the opposite direction will release the bolt so that the removable member of a bracket may be quickly detached from the flange 19 of the fixed bracket member.

The two removable bracket members are similar in construction except that the portion 22 of the left hand bracket 12 is longer in the direction of the adjacent edge of the platform than the portion 22 of the right hand bracket 14, and consequently, the channel 25 of the bracket 12 is also considerably longer than the channel of the bracket 14. This enables the brackets to be readily adapted for use with typewriter housings or bases of various widths, since the base members of the brackets are secured to the platform in such manner that the rear portion of the base or frame of the typewriter may extend between the base members of the brackets. For this purpose, the portion 22 of the left hand bracket is provided with additional pairs of apertures, as clearly shown in Fig. 3, through which the bolts 24 may pass when the brackets are spaced farther apart to accommodate typewriters of greater widths.

The bracket part 14 on the right-hand side of the copyholder is preferably provided with a pair of upwardly extending spaced ears or lugs 42 which may be secured to or formed integral with the upstanding reinforcing flange 28. These two ears or lugs are spaced apart to receive a lever 43 such as commonly used in connection with a copyholder to raise and lower the copy supporting part 44 thereof, and this lever 43 may, consequently, be connected with the lugs 42 by means of a pivot pin or bolt 46. By means of this construction, the copyholder lever, being mounted on a removable bracket member which in turn is secured to the copyholder, will remain in correct relation to the copyholder when the same is removed from the desk platform.

The brackets described have the advantage that they rigidly support the copyholder on the platform of the desk, and furthermore, support the same beyond the outer edge of the platform so as to leave ample room on the platform for the type-

writer or other machine. The fixed bracket parts are of such size as not to interfere with the movement of the platform 9 with the machine mounted thereon into the desk pedestal.

It will be understood that various changes in the details, materials, and arrangements of parts which have been herein described and illustrated in order to explain the nature of the invention, may be made by those skilled in the art within the principle and scope of the invention, as expressed in the appended claims.

I claim as my invention:

1. A bracket for removably supporting a copyholder on a desk platform, said bracket including a base member secured to the desk platform, a second member having a portion to which a copyholder may be secured and another portion which may be releasably secured to said base member, a truss member arranged in a substantially vertical plane and having its ends secured to said two portions of said second member to prevent bending of the same due to the weight of said copyholder, and a quickly releasable connection between said second member of said bracket and said base member to permit said copyholder together with said second member to be quickly mounted on and disconnected from said base member.

2. A bracket for removably supporting a copyholder on a desk platform, said bracket including a base member secured to the desk platform and having a supporting flange spaced from said platform, a second member having a portion to which a copyholder may be secured and another portion which may be releasably secured to said base member, a truss member connecting said two portions of said second member to prevent bending of said second member in one direction, and a reinforcing member extending transversely of said truss member and formed integral with said second member to prevent bending of said member in another direction, and a quickly releasable connection between said second member and said base member.

3. A bracket according to claim 2, in which said reinforcing member is of inverted U-shape in cross section and extends upwardly above said copyholder supporting portion of said second member.

4. A bracket according to claim 2, in which said reinforcing member is of inverted U-shape and extends upwardly from and connects said two portions of said second member and in which said truss member straddles said reinforcing member.

5. In a bracket for removably supporting a copyholder on the platform of a desk having a pedestal which may be closed by a door, that improvement in which the supporting bracket includes a base member secured to said platform and having a supporting flange spaced above said platform when the same is in substantially horizontal position, a second member having a portion to which a copyholder may be secured and another portion which may be releasably secured to said supporting flange of said base member, said second member having an intermediate portion which is bent into inverted U-shape and which connects said first mentioned two portions of said second member, said U-shaped portion being formed to straddle the upper portion of said door when the same is in open position, and a quickly releasable connection between the second member of said bracket and said flange of said base member to permit

removal of said copyholder and said second member from said base member and desk platform.

6. In a bracket for removably supporting a copyholder on the platform of a desk having a pedestal which may be closed by a door, that improvement in which the supporting bracket includes a base member secured to said platform and having a supporting flange spaced above said platform when the same is in substantially horizontal position, a second member having a portion to which a copyholder may be secured and another portion which may be releasably secured to said supporting flange of said base member, said second member having an intermediate portion which is bent into inverted U-shape and which connects said first mentioned two portions of said second member, said U-shaped portion being formed to straddle the upper portion of said door when in open position, a truss member which straddles said U-shaped part of said second member and which has one end thereof secured to said portion of said second member to which said copyholder is secured and which has the other end thereof secured to said portion of said second member which is releasably secured to said base member, and a quickly releasable connection between the second member of said bracket and said flange of said base member to permit removal of said copyholder and said second member from said base member and desk platform.

7. A bracket for releasably supporting on a desk platform a copyholder having a lever for vertical adjustment of a part thereof, said bracket including a base member rigidly secured to the desk platform and a second member having a horizontally extending portion to which a copyholder may be secured and another horizontally extending portion which may be releasably secured to said base member, reinforcing parts on said second member including an upwardly bent flange to resist flexing of the same due to the weight of said copyholder, the bracket having a portion on which said lever is pivoted to permit said lever to be swung to actuate said adjustable part of said copyholder, and a quickly releasable connection between said other portion of said second member and said base member.

8. A pair of brackets for releasably supporting on a desk platform opposite ends of the lower portion of a copyholder having a lever for vertical adjustment of a part thereof, each of said brackets including a base member rigidly secured to the desk platform and a second member having a portion to which a copyholder may be rigidly secured and another portion which may be releasably secured to said base member, an upwardly extending reinforcing part on said second member to resist flexing of the same due to the weight of said copyholder, the reinforcing part of said second member of one of said brackets having a pair of upwardly extending parts thereon spaced from each other and having an aperture extending through the same, a pivot pin extending through said apertures and through said lever for permitting said lever to swing to actuate said adjustable part of said copyholder, and quickly detachable connections between said second member of each bracket and the base member thereof to permit quick removal and replacement of said copyholder, said second members and said lever as a unit from said base members of said brackets.

9. A bracket for removably supporting a copyholder beyond an edge of a desk platform, said bracket including a base member secured to said

desk platform, a second member having a portion formed to be removably secured to said base member and another portion extending beyond said edge of said desk platform and to which a copyholder may be secured, a reinforcing portion extending in a direction substantially parallel to the adjacent edge of said platform and formed integral with said second member by bending a portion of said second member in a direction substantially perpendicular to the portion of said second member to which said copyholder is secured, and a truss member extending in a direction transversely of said reinforcing member and having portions thereof rigidly secured to said portion of said second member on which the copyholder is supported and to the portion of said second member which is secured to said base member.

10. A bracket for removably supporting a copyholder beyond an edge of a desk platform, said bracket including a base member secured to said desk platform and having a substantially horizontal supporting flange spaced from said platform, a second member having a substantially horizontal portion formed to seat on said supporting flange, and another substantially horizontal portion extending beyond said edge of said desk platform and to which a copyholder may be secured, an upright flange formed integral with said first mentioned portion of said second member, said second member having an integral reinforcing part of substantially inverted U-shape arranged between said portions thereof and formed integral with said second member by bending the same, said U-shaped part extending substantially parallel to said edge of said platform, and a substantially upright truss member extending crosswise of said U-shaped reinforcing part and having the end portions thereof rigidly secured to said horizontal portions of said second member.

11. A bracket for releasably supporting on a desk platform a copyholder having a lever for

vertical adjustment of a part thereof, said bracket including a base member secured to said desk platform and having a substantially horizontal supporting flange spaced from said platform, a second member having a substantially horizontal portion formed to seat on said supporting flange, and another substantially horizontal portion extending beyond said edge of said desk platform and to which a copyholder may be secured, an upright flange formed integral with said first mentioned portion of said second member, said second member having an integral reinforcing part of substantially inverted U-shape arranged between said portions thereof and formed integral with said second member by bending the same, said U-shaped part extending substantially parallel to said edge of said platform, and a substantially upright truss member extending crosswise of said U-shaped reinforcing part and having the end portions thereof rigidly secured to said horizontal portions of said second member, said flange having an upward extension formed integral therewith and on which said lever is pivoted to permit said lever to be swung to actuate said adjustable part of said copyholder.
